B. E. EDWARDS.

STAMP AND ENVELOP MOISTENER.
APPLICATION FILED DEC. 15, 1916.

1,222,940.

Patented Apr. 17, 1917.

Inventor
Boulder B. Edwards

By John H. Tracy, Attorney

UNITED STATES PATENT OFFICE.

BEULAH E. EDWARDS, OF LISCOMB, IOWA.

STAMP AND ENVELOP MOISTENER.

1,222,940.

Specification of Letters Patent. Patented Apr. 17, 1917.

Application filed December 15, 1916. Serial No. 137,206.

To all whom it may concern:

Be it known that I, BEULAH E. EDWARDS, a citizen of the United States, residing at Liscomb, in the county of Marshall and State 5 of Iowa, have invented certain new and useful Improvements in Stamp and Envelop Moisteners, of which the following is a specification.

My invention relates to new and useful 10 improvements in devices for moistening stamps, envelops and the like, the primary object of my invention being the provision of a device in which a liquid container is supported by a hinged arm so that it may 15 be swung to inverted position to discharge a predetermined quantity of its contents upon the article to be moistened.

In this connection, one of the primary objects of my invention consists in providing 20 the liquid container with a discharge spout and nozzle which will govern the quantity of liquid discharged and which is provided with a closure or cap which will prevent loss from evaporation when the device is not in 25 use.

A still further object of my invention consists in providing means for yieldably supporting the container in spaced relation to the base in either active or inactive position.

Another object which I have in view is the provision of a supplemental moistening device in the form of a pad which may receive moisture from the container and which may then be employed for moistening relatively 35 large areas, such as the gummed surface of envelops, wrappers and the like.

With these and other objects in view, my invention will be more fully described, illustrated in the accompanying drawings, and 40 then specifically pointed out in the claims which are attached to and form a part of this application.

In the drawings:

Figure 1 is a side elevation of my stamp 45 moistening device;

Fig. 2 is a fragmentary perspective view;

Fig. 3 is a fragmentary sectional view,

showing the container spout and its nozzle;

Fig. 4 is a fragmentary perspective view,

50 showing the additional moistening device in

cooperative arrangement with the nozzle or

spout of the container.

Corresponding and like parts are referred to in the following description and indicated 55 in all the views of the drawings by the same reference characters.

My invention, broadly, consists in a liquid container 10 mounted upon a hinged supporting member 11 which is swingingly carried by a base 12. More specifically, the 60 base 12, which is preferably substantially rectangular in shape, is formed of wood, iron or other material having sufficient weight to prevent accidental displacement of the device upon a desk or table and at one 65 end carries a table or platform 13 which may also be of wood or metal, as preferred. The supporting arm or bracket 11 is hinged to the inner end of the table, as shown at 14, and at its outer end is provided with a laterally directed arm 15 which engages against the outer wall of the container and serves as a means for attachment thereto. The container, the shape of which is best 70 shown in Fig. 2, has a flat bottom 16 and is provided with a reduced outwardly and upwardly extending arcuate spout portion 17 having a square terminal 18 which is open and which constitutes a discharge spout. The container is secured to the bracket arm 80 11 by rivets or other suitable fastening means 19 in such a manner that its spout portion is most remote from the hinge 14 and is formed in its bottom with a filling opening 20 which may be closed by a stopper 21, of cork, rubber or other suitable material. The outer end of the opening 20 may be flared, as at 22, to facilitate filling.

A ring or band 23, of some suitable non-corrosive metal such as aluminum, is secured about the end of the spout, projecting beyond such end and being formed with an inwardly directed supporting shoulder 24 so that a nozzle plate 25 may be secured across the spout and held in engagement therewith. This nozzle plate is provided with a plurality of uniformly distributed minute openings 26 through which the contents of the container may pass when the container is in inverted position, as shown in dotted lines at the left of Fig. 1.

A leaf spring 27 is secured at one end to the bottom of the container, as shown at 28, adjacent the lower end of the handle 20 and at its other end freely engages against the under face of the bracket or supporting arm 11 so that the spring may serve as a cushion to prevent injury to the container when it is swung to the position shown in dotted lines at the right in Fig. 1. When 105 the container is used, it is swung to the position shown in dotted lines at the left in this 110

same figure and, for a reason which will be later apparent, a helical spring 29 is fixed to the table 13 to engage the supporting arm 11 and act to hold the container with its 5 nozzle in spaced relation to the outer end of the table.

In use, assuming that the container is filled with water, a stamp to be moistened, or that portion of the envelop to which the 10 stamp is to be applied, is positioned upon the table in such a manner that when the container is swung to the position shown in dotted lines at the left in Fig. 1, its nozzle band 23 will encircle the stamp or envelop 15 surface. This position may be readily determined by suitable rulings upon the upper face of the table 13. When the stamp has been so positioned, the container is swung about the hinge 14 as a center, the spring 27 20 furnishing a convenient handle for accomplishing this, and is then forced downwardly against the action of the spring 29 to bring the nozzle ring in engagement with the table, as shown in Fig. 3. After sufficient 25 water has passed through the nozzle onto the stamp, the container may be released when the spring 29 will elevate it as shown in full lines in Fig. 1 to such an extent as to permit the withdrawal of the 30 stamp or envelop and also prevent further passage of water to the nozzle. If no more stamps or envelops are to be moistened, the container will, of course, be immediately 35 swung to the position shown at the right in Fig. 1 of the drawings. If, on the other hand, further stamps are to be moistened, they will be successively placed upon the table while the container is held in elevated position by the spring 29 and moistened by 40 depressing the container against the action of this spring.

A nozzle cover 30, formed of the same material as the nozzle, is provided having a marginal flange 31 to embrace the band 23 45 so that the cover may be held in place upon the container when the device is not in use to prevent evaporation of water from the container. At this point it should be noted that the nozzle of the container is preferably 50 of the shape and dimensions of the stamps to be moistened.

In many instances, it is necessary to moisten a considerable surface, as in sealing envelops, packages and the like, and for 55 this purpose I provide a pad 32, of absorbent material, capable of fitting within the nozzle band 23 and provided with a wire handle 33 terminating in a loop 34 by means of which the pad or sponge may be conveniently manipulated. When this pad is to be 60

employed, it is positioned upon the table in the same manner as a stamp would be and the container is swung into position to discharge water upon it.

Although I have illustrated and described 65 my invention in all its details, it will of course be understood that I do not wish to be limited to such details, but reserve the right to make any changes, within the scope of the appended claims. 70

Having thus described the invention, what is claimed as new is:

1. A device of the character described including a hinged supporting member, a container carried by the free end of the member and adapted in one position of the member to be disposed in an upright position and in another in an inverted position, and a nozzle controlling passage of fluid from the container when in inverted position, said 80 nozzle including a perforate member positioned across the discharge opening of the container, and a retaining band engaging about the container and having a shoulder engaging the perforate member. 85

2. A device of the character described, a supporting base, an arm hinged to the intermediate portion of the base, a container fixed to the free end of the arm, a spring secured to the container and resting against 90 the arm to cushion the arm from the base, and resilient means for holding the arm in position to space the container above the base when the arm is swung to invert the container. 95

3. A device of the character described including a supporting base, an arm hinged at one end near the center of the base, a semi-spherical container having a closed flat bottom secured to the free end of the arm, the 100 container having a curved spout, and a discharge nozzle controlling passage of fluid through the spout.

4. A device of the character described including a supporting base, an arm hinged at one end near the center of the base, a semispherical container having a closed flat bottom secured to the free end of the arm, the container having a curved spout, a discharge nozzle controlling passage of fluid 110 through the spout, said nozzle including a band projecting beyond the spout, a perforate member engaging the end of the spout and encircled by the band, and a pad of absorbent material capable of seating 115 within the band and against the perforate member.

In testimony whereof I affix my signature.

Mrs. BEULAH E. EDWARDS. [L. s.]
